WILLIAM H. CARD AND JOSEPH J. CUSHMAN, OF LOS ANGELES, CALIFORNIA.

STARTER FOR INTERNAL-COMBUSTION ENGINES.

1,230,064.

Specification of Letters Patent. Patented June 12, 1917.

Application filed July 27, 1916. Serial No. 111,599.

To all whom it may concern:

Be it known that we, WILLIAM H. CARD and JOSEPH J. CUSHMAN, citizens of the United States, residing at Los Angeles, in the county of Los Angeles and State of California, have invented new and useful Improvements in Starters for Internal-Combustion Engines, of which the following is a specification.

10 This invention relates to an engine starter and particularly pertains to a starting device adapted to be used in connection with automobile engines.

It is an object of this invention to provide an engine starter which may be simply mounted upon the crank shaft of the engine and which may be readily operated from the driver's seat to turn the engine crank shaft and thus start the motor.

20 Another object is to provide the device with simple clutch means which are only operable when the starting device is actuated and which will act in a positive manner to engage the crank shaft of the engine and 25 will further insure that the starting device will not be objectionably rotated should the engine back fire.

Another object is to provide means for 30 insuring that the clutch will be released from engagement with the shaft upon the release of the operating member by the driver, and will remain in a disengaged position until the operating member is fully drawn to start the car.

35 It is another object to provide a starter having few parts which are adapted to be assembled in an easy manner and which coact in performing their functions so that they are not liable to become worn or to 40 require repair.

Another object is to provide a simple and effective oiling system for the starter whereby oil will be circulated to all the parts requiring lubrication and will be there retained.

45 It is a further object to provide a self-starter which may be operated with small effort and which is decidedly cheap in manufacturing costs.

50 Other objects will appear hereinafter.

The invention is illustrated by way of example in the accompanying drawings in which:

55 Figure 1 is a view in elevation illustrating the starter in its operative position upon an engine shaft.

Fig. 2 is a view in horizontal section on the line 2—2 of Fig. 1 and illustrates the vital parts of the device in their starting position.

60 Fig. 3 is a view in section similar to Fig. 2 and illustrates the normal disengaged positions of the vital parts of the device.

Fig. 4 is a view in plan illustrating in a diagrammatical manner the arrangement of 65 parts and application of the device as applied to an automobile engine.

Referring to the drawings more particularly, 10 indicates the end of an automobile crank shaft and is here shown as having 70 a sleeve 11 mounted thereover and secured by a pin 12. This sleeve is formed with an annular shoulder at a point adjacent its outer end, said shoulder being formed with a frusto-conical portion 14, the apex of 75 which would theoretically lie upon the longitudinal axis of the crank shaft and toward the body of the engine. An extension 15 is formed on the outer end of the sleeve portion 11 and is of a suitable diameter to 80 receive the hub of an ordinary starting crank which is adapted to engage a starting pin 16. The frusto-conical portion 14 of the sleeve 11 is encircled by and borne against by an annular split cup 17 which is formed 85 with an internal conical face adapted to coincide with the face of the portion 14. This cup has its ends formed with radially extending ears 18 and 19 which are spaced a short distance from each other and which 90 may be forced toward each other by means which will hereafter be described. The cup 17 is formed with a flat end face which bears against the end face of an annular cone member 20 which is formed with a 95 central bore adapted to pass over the tubular portion of the sleeve 11. This cone has an external frusto-conical face 21 converging at a point toward the engine and adapted to be pressed into engagement with a 100 complementary cone-cup 22 formed in the outer end of a fan pulley wheel 23 which is secured upon the engine shaft and over the tubular portion of the sleeve 11 by the pin 12. It is evident that the member 23 need 105 not necessarily be utilized as a fan pulley wheel but may be formed as a special cup for the starter construction only.

As a means for lubricating the various cones and cups and the sleeve upon which 110 they rotate, grease pockets 24 and 25 are alternately arranged concentrically around

and through the cone 20. The pockets 24 extend entirely through the cone, and the pockets 25 extend a portion of the way through so that grease may be retained within the device and readily distributed therethrough.

The cone 20 is formed with an extension plate 26 which extends outwardly from the periphery of the cone in a radial manner and is provided with a pivot pin 27 upon which an operating arm 28 is pivotally mounted. The arm 28 is bent and has a substantially vertical portion 29 and a horizontal portion 30, to the end of which a vertically extending link 31 is pivotally secured upon a pin 32. The link 31 is formed with a perforation 33 within which the end of a chain or cable 34 is secured.

The cable 34 affords connection between the starting device and a draw-bar 35 by which the operator manipulates the starting mechanism. This draw-bar preferably extends through an opening in the dash-board 36 of the automobile and communicates with the upper end of a vertically pivoted simple lever 37 which is held by means of a pivot pin 38 upon the frame of the car. One end of the chain 34 engages the lever at a suitable point along its length to provide the required leverage for the starter, and thereafter passes around an idler pulley 39 from whence it is led to the link 31 of the arm 28. A spring 40 is secured to the operating arm 28 and acts to retract the arm to a normal position after having been pivotally moved by a pull upon the chain 34.

The split cup 17 is adapted to be contracted in the operation of the device by forcing the ears 18 and 19 toward each other. This is accomplished by allowing the ear 19 to bear against a pin 41 rigidly secured to the plate 26 and forming an engaging lug 42 upon an extension of the operating arm 28 so that movement of the operating lever 45 in the direction of the arrow —a— will swing the lug 42 in a general direction toward the pin 41 and will thereby bind the ears 18 and 19 therebetween. A reinforcing link 43 connects the pivot pin 27 and the pin 41 to aid in strengthening the device and to retain the movable members in their operative position.

When the starter has been assembled as described and secured upon the drive shaft 55 in the proper manner, it may be operated as follows:

Assuming that the engine control valves are in proper position to cause an explosion within the engine cylinders, the draw-bar 60 35 is drawn, by means of a suitable handle, in the direction indicated by the arrow —b— and will thereby swing the lever 37 upon its pivot to draw the chain 34 and swing the operating arm 28 upon the pivot 65 27 in the direction of the arrow —a—. This

arm, when so swung, will force ears 18 and 19 of the cup 17 toward each other and thereby reduce the diameter of the cup and cause it to slide inwardly upon the frustoconical face 14 of the shoulder on the sleeve 70 11. This action will force the cone 21 into the cup 22 within the pulley 23 and bind them together frictionally. When these parts are thus locked, further movement of the chain 34 as it pulls the operating arm 75 28 will swing the cone 20 and the pulley 23 a portion of a revolution and as the pulley is pinned to the shaft 10 of the engine it will also rotate. This rotation of the shaft is sufficient to properly start the engine 80 under normal conditions and when the engine is slow in starting the operation may be repeated by reciprocating the bar 35 until an explosion occurs. In case of back fire within the engine the cone 20 will slip upon 85 its seat and thereby prevent dangerous shocks liable to be delivered to the operator as he holds the handle of the draw-bar.

It will thus be seen that this starter is formed with few operative parts and that 90 it may be easily operated to rotate an automobile engine crank shaft while the operator is seated and that it further insures against harm to the operator while starting.

We claim:

1. In an engine starter, the combination with an engine crank shaft, of a starter sleeve secured thereon, a fixed clutch member secured thereover, a loose clutch member adapted to rotate upon and move along 100 said fixed member, means whereby the loose clutch member may be rotated upon the sleeve, a shoulder formed at the outer end of said sleeve, and means acting between said shoulder and the loose clutch member and actuated by said clutch rotating means to force the loose clutch member into engagement with the fixed member.

2. In an engine starter, the combination with an engine crank shaft, of a fixed clutch 110 member having a cone-shaped recess in one side thereof and concentric with the crank shaft upon which it is secured, a loose clutch cone slidably mounted in relation to the cone-shaped recess, a sleeve upon which said cone is adapted to rotate, an annular conical shoulder adjacent the outer end of said cone, a split conical cup adapted to bear between the conical shoulder and the cone, means whereby the cone may be rotated, 120 and means acting simultaneously with the rotation of the cone whereby the split conical cup will be contracted around the conical shoulder and will act to force the cone into engagement with the fixed clutch member to 125 rotate the engine shaft.

3. In an engine starter, the combination of an engine crank shaft, a fixed clutch member thereon, a second clutch member slidably mounted on said shaft, means 130

loosely mounted on said shaft for moving said second clutch member longitudinally along said shaft in frictional engagement with said fixed clutch member, means pivoted to said loose clutch member for simultaneously actuating said first named means and imparting a partial rotation to said second clutch member, and resilient means tending to move said pivoted means into 10 normal inoperative position.

4. In an engine starter, the combination with an engine crank shaft, a fixed clutch member thereon, a second clutch member slidably mounted on said shaft, means for 15 moving said second clutch member longitudinally along said shaft in frictional engagement with said fixed clutch member, means for simultaneously actuating said first named means and imparting a partial rotation to said second clutch member, and means tending to move said last named 20 means into normal inoperative position.

5. In an engine starter, the combination

with an engine crank shaft, a fixed clutch member thereon, a second clutch member 25 slidably mounted along said shaft, means for moving said second clutch member longitudinally along said shaft in frictional engagement with said fixed clutch member, and means imparting a partial rotation to said 30 second clutch member.

6. In an engine starter, the combination with an engine crank shaft, a fixed clutch member thereon, a second clutch member 35 slidably mounted along said shaft, and means for simultaneously moving said second clutch member along said shaft in frictional engagement with said fixed clutch member and for imparting a partial rotation to said second clutch member, and 40 means tending to move said last named means into normal inoperative position.

In testimony whereof we have signed our names to this specification.

WILLIAM H. CARD.
JOSEPH J. CUSHMAN.
